Primary Examiner—Ian Simmons

(74) Attorney, Agent, or Firm—Cummings & Lockwood

(57) **CLAIM**

The ornamental design for a vial, as shown and described.

DESCRIPTION

FIG. 1 is a side elevational view of a first embodiment of a vial showing our new design;

FIG. 2 is a top perspective view of the vial of FIG. 1;

FIG. 3 is a bottom plan view of the vial of FIG. 1;

FIG. 4 is a top plan view of the vial of FIG. 1;

FIG. 5 is a side elevational view of the vial of FIG. 1 with the cap removed;

FIG. 6 is a top perspective view of the vial of FIG. 5;

FIG. 7 is a bottom plan view of the vial of FIG. 5; and,

FIG. 8 is a top plan view of the vial of FIG. 5.
